(57) **CLAIM**

The ornamental design for a novelty purse, as shown and described.

DESCRIPTION

FIG. 1 is a front isometric view of the first embodiment of our new purse;

FIG. 2 is a rear isometric view of the preferred embodiment; FIG. 3 is a front elevational view of the preferred embodiment;

FIG. 4 is a left side elevational view of the preferred embodiment;

FIG. 5 is a right side elevational view of the preferred embodiment;

FIG. 6 is a top plan view of the preferred embodiment;

FIG. 7 is a bottom plan view of the preferred embodiment; FIG. 8 is a rear elevational view of the preferred embodiment;

FIG. 9 is a front isometric view of the second embodiment of our new purse; and,

FIG. 10 is a rear isometric view of the second embodiment. The crisscross pattern of lines in the drawings represent material and is understood to be continuous throughout the implied areas.
